MOTION PICTURE CAMERA WITH REVERSIBLE BODY

Jan Hampl, Prerov, and Zdenek Sekora, Marianske Udoli,
near Olomouc, Czechoslovakia, assignors to Meopta,
narodni podnik, Prerov, Czechoslovakia, a corporation
of Czechoslovakia

Filed Feb. 5, 1963, Ser. No. 73,444

Term of patent 14 years

Claims priority, application Czechoslovakia Aug. 10, 1962

(Cl. D61—1)

FIG. 1 is a left-side perspective view of a motion picture camera with reversible body showing our new design;

FIG. 2 is a right-side perspective view thereof;

FIG. 3 is another right-side perspective view showing the camera body partially swiveled; and

FIG. 4 is a rear perspective view thereof.

We claim:

A motion picture camera with reversible body, substantially as shown.
